UNITED STATES PATENT OFFICE.

JOSEPH C. SMITH, OF MOUNT VERNON, NEW YORK, ASSIGNOR TO THE J. B. BREWSTER & COMPANY, OF NEW YORK.

DESIGN FOR A CARRIAGE-BODY.

SPECIFICATION forming part of Design No. 20,041, dated July 15, 1890.

Application filed April 5, 1890. Serial No. 346,734. Term of patent 14 years.

To all whom it may concern:

Be it known that I, JOSEPH C. SMITH, a citizen of the United States, residing at Mount Vernon, in the State of New York, have invented and produced a new and original Design for Carriage-Bodies, of which the following is a specification, reference being had to the accompanying drawings, forming part thereof.

10 Figure 1 is a side view of a body constructed according to my design. Fig. 2 is a vertical section through the line 2 2 of Fig. 1 of one of the panels detached from the remainder of the body of the carriage.

15 The leading feature of my design consists of the panel on the carriage-body, from the surface of which ribs rise and die out at their ends into the surface, leaving a well-defined space between the marginal molding or edge 2c of the panel and ends of the ribs.

a is a panel.

b b' b² b³ is a series of moldings or ribs, which are fixed to the face of the panel in such manner that the portion thereof projecting from the face of the panel is of the form shown in Fig. 2, being tapered down toward each extremity, so that the outside face of each rib dies into the surface of the panel, as at c c'.

d d' is another molding, which may be employed around the edge of the panel. 30

What I claim is—

The design for carriage-bodies herein shown and described.

JOSEPH C. SMITH.
